INTAKE AND MIXING DEVICE

Frank Reid, Williams, Minn.

Application December 11, 1937, Serial No. 179,368

3 Claims. (Cl. 123—119)

My invention relates to improvements in air intake and mixing devices for the carburetors of internal combustion engines.

The object of the invention is to provide efficient, inexpensive means of the character above indicated which may be readily incorporated with present day carburetors as part of the equipment thereof to automatically vary the mixture drawn from the carburetor in accordance with different operating requirements, as, for instance, in hot or cold weather, and when the engine is hot or cold, and which embodies devices for effectively breaking up particles in the mixture which have not been completely vaporized and is equipped to thoroughly filter the auxiliary air.

Other objects more subordinate in nature will appear when the succeeding description is read with reference to the drawings accompanying and forming part of this specification, it being understood that the invention resides in the details of construction and combinations of parts illustrated in said drawings, specifically treated in said description, and defined in the claims appended hereto.

In said drawings:—

Figure 1 is a fragmentary view in side elevation illustrating a preferred embodiment of the invention.

Figure 2 is a view in top plan, parts showing in section.

Figure 3 is a view in vertical transverse section taken on the line 3—3 of Figure 2 looking in the direction indicated by the arrows.

Figure 4 is a similar view taken on the line 4—4 of Figure 2 looking in the direction of the arrows.

Figure 5 is a view in transverse section taken on the line 5—5 of Figure 4 looking downwardly, and

Figure 6 is a view in top plan of the fan mounting.

Referring to the drawings by numerals, in the illustrated embodiment thereof my invention has been shown as applied to a down-draft type of carburetor, the outlet or discharge conduit 1 thereof being shown only since the remainder of the carburetor is unimportant as regards a proper understanding of the invention. The conduit 1 has the usual flange 2 thereon for bolting to the corresponding flange 3 of the usual intake manifold 4 having the throttle valve 5 therein.

According to my invention an air intake and mixing unit 6 is interposed between the flanges 2 and 3, or in other words, between the car-

buretor and intake manifold 4, said unit being constructed and arranged as follows:

The basic element of the unit 6 is a plate-like air jet member 7 fitting between said flanges 2 and 3 and having a central aperture 8 therein corresponding in size with the bore of the conduit 1 and manifold 4 and registering therewith. A pair of inlet ports 10, forming air jets, are formed in opposite sides of the member 7, respectively, said ports extending tangentially to 10 the aperture 8 and opening therewith in opposite directions on opposite sides thereof but in a common horizontal plane. Within the member 7 is a fan 11 suspended from a cross bar 12, for rotation in said plane, by means of a screw bolt 13 passing through the hub 14 of said fan and into said bar. The cross bar 12 is part of an open frame 15 disposed on the member 7 and shown in part in Figure 6. Disposed on top of the frame 15 is a similar frame 16 from the inner edge of which a plurality of pairs of opposed baffles 17 extend into the conduit 1. The baffles 17 and frame 16 are formed of thin metal, the baffles with shanks 18 terminating in rounded button-like ends 19 and twisted to dispose said ends 19 in planes oblique to the horizontal, the ends of each pair of baffles being twisted in opposite directions and located in a circular group concentric to the axis of the fan 11. Below the member 7 is a filter screen 20 formed of a sheet of any suitable reticulative material and having its edges interposed between said member and the flange 3. The member 7, frames 15 and 16, and the filter screen 20 are clamped between the flanges 2 and 3 by means of bolts 21 and nuts 22 thereon arranged at suitable intervals around said flanges.

At one side of the described unit 6 is an air control unit 23 comprising a closed cylindrical container 24, of any suitable metal, suspended from the flange 3, preferably, by means of a bracket 25 fixed to and extending from the container 24 and clamped to the flange 3 by means of one of the aforementioned bolts 21 and nuts 22. Extending into the container 24, through the top thereof and at the side thereof opposite to the unit 6, is a vertically disposed air intake pipe 25 spaced slightly at its lower end from the bottom of said container. Extending from the top of the container 24, at the side thereof opposite the pipe 25, is a pair of discharge pipes 26 suitably connected to the member 7 to discharge air into the aforementioned ports 10. The container 24 is designed to contain oil to approximately the level indicated by the dotted line 27 55

in Figure 4. Intermediate the oil level 21 and the container ends of the discharge pipes 26 is a plate-like splash guard 28 extending from the wall of the container and suitably secured thereto in horizontal position. At one side thereof a glass sight panel 29 is suitably secured to the container 24 over a sight opening 30 provided therein whereby the level of the oil in the container may be always ascertained.

Referring to the operation, under the suction created in the intake manifold air is drawn into the member 7, and hence into said manifold, through air intake pipe 25 the oil in the container 24, discharge pipes 26, and ports 10, this auxiliary air being cleaned or filtered by its passage through the oil in the container 24. Manifestly the quantity of auxiliary air introduced into the manifold 4 is determined primarily by the speed of the engine as controlled by the throttle valve 5 so that when the engine is running at high speed, the throttle valve 5 being well open, the quantity of air introduced is increased and the mixture from the carburetor correspondingly thinned thereby conserving fuel as will be manifest. On the other hand as the engine decelerates under closing movement of the throttle valve 5 the quantity of auxiliary air introduced in the manner described is cut down. As the auxiliary air is drawn into the member 7 by way of the ports 10 it issues from said ports in the form of jets directed against the blades of the fan 11 and causing rotation of the latter in a direction to draw or accelerate discharge of the mixture from the conduit 1. Such discharge of the mixture, however, is opposed by the baffles 17 which, together with the fan 11, tends to break up particles of gasoline in the mixture which have not been completely vaporized in the carburetor mixing chamber. Such breaking up of the mixture is further facilitated by its passage through the filtering screen 20 as will be clear.

As will be understood, the oil in the described air-control unit 23 functions to regulate the quantity of air passing through said unit under different temperatures obtaining. For instance, in cold weather, when a rich mixture is desirable for starting and warming up the engine, the oil is thicker and retards the passage of air therethrough. In warm weather, the oil being thinner, there is less resistance to passage of the air therethrough as will be clear.

The operation, construction and advantages of my invention will, it is believed, be clearly understood from the foregoing without further explanation.

It may be stated, however, that although the invention has been shown and described as applied to a down-draft carburetor, it may be utilized

with up-draft carburetors by merely reversing the position of the described unit 6.

Manifestly other modifications, than that above indicated, may be resorted to without departing from the inventive concept and right is herein reserved to all such modifications falling within the scope of the subjoined claims.

What I claim is:

1. The combination with a carburetor and the intake manifold of an internal combustion engine, of an auxiliary air supply and mixing unit in the line of connection between said carburetor and manifold comprising a ring-like member, a fan rotatably mounted in said member, said member having a plurality of jet forming air inlet ports therein adapted under suction created in said manifold to discharge jets of air against said fan whereby the latter is rotated, a plurality of baffle fingers extending inwardly of the member over said fan, and means for introducing auxiliary air to said ports comprising an oil container through which said auxiliary air is passed.

2. The combination with a carburetor and the intake manifold of an internal combustion engine, of an auxiliary air supply and mixing unit in the line of connection between said carburetor and manifold comprising a ring-like member, a fan rotatably mounted in said member, said member having a plurality of jet forming air inlet ports therein adapted under suction created in said manifold to discharge jets of air against said fan whereby the latter is rotated, a plurality of baffle fingers extending inwardly of the member over said fan, and means for introducing auxiliary air to said ports comprising an oil container through which said auxiliary air is passed, and a filtering screen in said member below said fan.

3. The combination with a carburetor and the intake manifold of an internal combustion engine, of an auxiliary air supply and mixing unit in the line of connection between said carburetor and manifold comprising a ring-like member, a fan rotatably mounted in said member, said member having a plurality of jet forming air inlet ports therein adapted under suction created in said manifold to discharge jets of air against said fan whereby the latter is rotated, a plurality of baffle fingers extending inwardly of the member over said fan, and means for introducing auxiliary air to said ports comprising an oil receptacle through which said auxiliary air is passed, an air inlet pipe extending through the top of the receptacle into the oil, conduits extending between the top of the receptacle and said ports, and a splash guard in the receptacle between the level of the oil and said conduits.

FRANK REID.
